ANTENNA

Roger E. Clapp, Cambridge, Mass., assignor, by
mesne assignments, to the United States of
America as represented by the Secretary of War

Application September 14, 1945, Serial No. 616,370

3 Claims. (Cl. 250—33.65)

1

This invention relates to antennas for radio communication systems and particularly to antennas having means for obtaining an energy distribution pattern closely approximating the relation of $csc^2\theta$ in elevation, where θ is the radiation angle measured from the axis of the radiating means or of the undistorted or symmetrical radiation pattern normally produced by the radiating means.

In certain radio object locating systems, it is 10 desirable that the energy distribution in a vertical plane be such that the variation of energy density versus the radiation angle approximates a cosecant-squared function. This distribution provides generally uniform echo strength for targets disposed at substantially equal elevation with respect to the antenna regardless of whether the target is close in or distant.

It is the principal object of the present invention to provide an antenna adapted to produce a radiation pattern of $csc^2\theta$ configuration which has a uniform ground return characteristic over a reasonable range of altitudes.

It is another object of the invention to provide a linear array antenna with reflector means for desired shaping the radiation pattern.

Other novel features and advantages of the invention will become apparent from the following description with reference to the accompanying drawings in which:

Fig. 1 is a partly diagrammatic side elevation of a linear array antenna illustrating one embodiment of the present invention and the radiation pattern produced thereby;

Fig. 2 is a side elevation similar to Fig. 1 showing a modification of the invention; and

Fig. 3 is a perspective view of a linear array antenna showing more clearly the reflecting means according to the modification of Fig. 2.

Referring now to Fig. 1, 10 designates a longitudinal wave guide having broad walls 11 and 12 and narrow walls 13 and 14. Along the length of broad wall 11 and substantially midway of the width thereof there are, physically mounted, a plurality of spaced aligned dipoles 15 of conventional design having means for coupling to the energy propagated in wave guide 10. As so far described, this generally constitutes a linear array scanning antenna such as is disclosed in the co-pending application Serial No. 542,287, filed June 27, 1944, in the name of Luis W. Alvarez. While the present invention is principally directed to a linear array antenna such as disclosed in the aforesaid co-pending application, it will be

2

understood that the invention is not limited thereto but may apply to any similar antenna.

On opposite sides of (or as shown above and below) the row of dipoles 15, there are mounted reflector plates 16 and 17. Reflector plate 17 is preferably a plane substantially rectangular sheet of electrically conductive material having one edge secured substantially along the length of wave guide 10 and at an acute angle to a plane through the dipoles 15 and perpendicular to broad wall 11. Reflector plate 16 is also a sheet of electrically conductive material having one edge secured along the length of wave guide 10 with its major portion also disposed at an acute angle to broad wall 11. The combination of plates 16 and 17 as seen in side elevation in Fig. 1 give the appearance of a horn flared outwardly away from wave guide 10 and the effect is similar to that of a flared horn with respect to the efficiency of radiation and impedance matching.

The outer edge portions of plate 16 has one or more, and preferably three, sharp bends or in other words is bent along its length one or more, and preferably three times in alternate directions, to produce the configuration shown in side view in Fig. 1, the bends appearing as substantially parallel lines in a top plan view. The free edge portion 18 of plate 16 is preferably bent downwardly toward plate 17 so that the side view configuration of the bent portion is substantially Z-shaped. Radiation from dipoles 15 impinges upon the angularly related surfaces of upper plate 16 and is generally reflected downwardly while plate 17 acts to reflect the energy ahead of the antenna and also acts to cut off sharply the lower portion of the radiation pattern. By suitable design of the bent portion or portions of plate 16 and of the angular relation of plates 16 and 17, any desired radiation pattern may be produced including a pattern of $csc^2\theta$ configuration as indicated by dotted lines in Fig. 1.

The radiation pattern obtained from the plates in Fig. 1 was found to be particularly satisfactory when the antenna was enclosed within a rounded leading edge type vane 19 as indicated in the dash lines of Fig. 1. The phasing of the reflection from plates 16 and 17 in combination with the reflections from the interior surface of the vane 19 was such that the radiation pattern had small secondary lobes and holes in the main lobe were sufficiently filled out to give uniform ground return through the scanning range. However, for a more streamlined vane 19' such as indicated in broken lines in Fig. 2, it was found that with the particular design of the reflector

plates 16 and 17 as shown in Fig. 1 the streamlined vane 19' caused some out-of-phase reflections. To overcome these disadvantages, the modification as shown in Figs. 2 and 3 was developed.

In Figs. 2 and 3, the parts similar to those described with reference to Fig. 1 are shown in prime numbers. Plates 16' and 17' are shaped and disposed in a similar manner as that described in Fig. 1 except that the rear edges of the plates are disposed forwardly of the broad wall 11'. Thus, the rear edges of plates 16' and 17' are connected to and along the forward edges of parallel plate members 20 and 21. The parallel plate members 20 and 21 are disposed substantially perpendicular to broad wall 11', above and below the row of dipoles 15' and may be secured directly to the broad wall 11'. Preferably, parallel plate portions 20 and 21, are disposed forwardly of the wave guide 10 so that the rear edges of plates 20 and 21 are substantially the same distance from wall 11' as the dipoles 15'. Thus, reflector plates 16' and 17', including the parallel plate portions 20 and 21 may be mounted on wave guide 10 by means of spaced supporting members 22 secured to broad wall 11 in any suitable manner (Fig. 3). If desired, flanges 23 and 24 are provided to insure greater strength, such flanges being disposed along the rear edges of parallel plate portions 20 and 21 and substantially parallel with wall 11'.

The effect of arranging the reflector plates 16' and 17' with the parallel plate portions 20 and 21 forwardly of the wave guide 10 as herein described is that the radiation from dipoles 15' is channeled by the parallel plate members 20 and 21, the phasing of the radiation is made more uniform and is effective to offset the out-of-phase reflections which would be caused by the vane 19' itself.

While there has been described what is at present considered the preferred embodiments of the invention, it will be obvious to those skilled in the art that various changes and modifications may be made therein without departing from the invention.

What is claimed is:

1. In a linear array antenna having a longitudinal wave guide, means for propagating energy within said wave guide, a plurality of dipoles aligned along one of the walls of said wave guide, means for shaping the radiation pattern produced by said dipoles, said means comprising two reflector plates one disposed above and the

other below said aligned dipoles, said reflector plates being arranged at an angle to said wall of said wave guide and flared outwardly away from each other, one of said reflector plates having a plurality of bends in alternate directions in the end portion remote from said wall to form a plurality of angularly disposed reflecting surfaces, said bends being substantially parallel lines along the length of said reflector plate, said angularly disposed reflecting surfaces being effective to direct energy radiated from said dipoles in any desired radiation pattern.

2. An antenna as claimed in claim 1 in which the reflector plates are connected along the rear edge to parallel plate portions disposed perpendicularly to the wave guide, and in which spaced supporting members connect said parallel plate portions and said reflector plates to said wave guide, whereby said reflector plates and said parallel plate portions are positioned forwardly of said wave guide and of said dipoles.

3. In a linear array antenna having a longitudinal wave guide, means for propagating energy within said wave guide, a plurality of dipoles aligned along one of the walls of said wave guide, means for shaping the radiation pattern produced by said dipoles, said means comprising two reflector plates one disposed above and the other below said aligned dipoles, said reflector plates being arranged at an angle to said wall of said wave guide and flared outwardly away from each other, one of said reflector plates having at least one bend along the length of the end portion remote from said wall, said bend being parallel to said wall and forming a secondary reflecting surface whereby an asymmetrical radiation pattern is obtained.
